C. I. LOPDELL,
BAND CLIP,
APPLICATION FILED AUG. 27, 1921.

1,412,188.

Patented Apr. 11, 1922.

INVENTOR

Charles I. Lopdell,
by
Hubert F. Gell,
Attorney.

UNITED STATES PATENT OFFICE.

CHARLES I. LOPDELL, OF SURBITON, ENGLAND.

BAND CLIP.

1,412,188.

Specification of Letters Patent. Patented Apr. 11, 1922.

Application filed August 27, 1921. Serial No. 496,156.

(GRANTED UNDER THE PROVISIONS OF THE ACT OF MARCH 3, 1921, 41 STAT. L. 1313.)

To all whom it may concern:

Be it known that I, CHARLES LEVERS LOPDELL, a subject of the King of Great Britain, and resident of 2, Westfield Place, Surbiton, 5 in the county of Surrey, England, have invented certain new and useful Improvements in Band Clips, for which I have filed an application for patent in England, No. 136,273, dated December 13, 1918, of which 10 the following is a specification.

This invention relates to band clips for clamping devices such as are used for attaching hose pipes to metal sockets or for clamping articles on to tubular metal members and so forth. It is the object of the 15 invention to provide a form of clip with a tightening device which shall be small and compact, and neat in appearance, while capable of exerting a powerful tightening action upon the articles to which it is applied.

The invention is illustrated in the accompanying drawings, wherein:

Figure 1 shows one form of the device in section;

Figure 2 shows an end view thereof, and Figure 3 shows a plan view.

Figure 4 shows in section a modified construction;

Figure 5 shows this latter in side elevation, and

Figure 6 shows it in plan.

Figure 7 shows an end view.

Figure 8 is a sectional detail view showing another method of attaching the end of 35 the band to the sliding plate.

Figure 9 is a sectional view showing another construction, and

Figure 10 is a plan thereof.

Figure 11 shows a construction similar 40 to that of Figure 8, but with the sliding plate inverted.

In the construction shown in Figures 1 to 3, the band 1 has its one end 2 which is adjustable in length, passed in and out of 45 two slots in the base of an L-shaped plate 3, while the other end of the band is passed freely through another more open slot at 5 in the plate 3, and is detachably gripped by its enlarged end 4 in a slot in the downwardly bent portion of a sliding plate 6. The enlargement at the end 4 is formed for 50 instance by wrapping the end of the band round a short length of wire. The plate 6 slides through a slot near the top of the upwardly turned end or lug 7 on the plate

3, through which works a screw 8, and the end of this screw bears against the end portion of the sliding plate 6. 14 is a nut through which screw 8 works, the nut being prevented from turning by engaging against the base of plate 3. Assuming the end 4 of the band to be gripped or attached to the plate 6, it will be seen that the band is tightened up by causing the screw 8 to move toward the left in Figure 1. The length of 65 the band 1 can be roughly adjusted on pulling its end 2 through the slots in plate 3, so as to leave a convenient length for tightening by the screw 8. In the example of construction shown, the end 4 of the band 70 is detachably gripped by means of a flap 9 hinged by lugs at 10 to the plate 6. When the band is loose, the flap 9 can be turned out at an angle as shown in dotted lines in Figure 1, and the end 4 of the band can be 75 passed easily through the slot at 11; but when the flap is flat against the end of plate 6 and the band is tightened, the enlarged end 4 of the band pulls against the end of the flap, and only a narrow slot is left 80 through which the end of the band cannot pass. When the screw 8 is loosened, the end 4 of the band can be released again at any time, so that the clip is readily detachable.

Any other convenient form of detachable connection between the end 4 of the band, and the sliding plate 6 may also be used. In the form of construction shown in Figures 4 to 7, the end 4 of the band is carried 90 over the overhanging end of sliding plate 6, passed through a slot at 12, and gripped between the end of plate 6 and a washer or plate 13 on the end of the screw 8. These figures also show the plate 3 formed with 95 only a single slot in its base portion through which both ends of the band are passed, the end 2 being merely doubled back on itself to form a stiff piece which cannot pull back under the end of plate 6 and the other end 100 of the band when tightened. The pull on the band 1 on the end 4 in fact tends to draw from the end of plate 6 so that it, and the end portion of the band which passes round the plate, are pressed down upon the doubled 105 end 2 of the band.

Figures 5, 6 and 7 show how the device may be made to have a neat appearance by being boxed in at the sides. The base 3 has side flaps 15 bent up to lie against the sides 110

of the lug 7, and formed with overhanging nibs 16 at the top to form guides under which the sliding plate 6 work, as seen in Figure 6. The side flaps 15 may be indented 5 as at 21, Figure 5, to engage in indentations in the ends of the nut 14, or the nut may be otherwise held in the box-like form of clip to prevent it from receding when the screw 8 is slackened.

10 Figure 8 shows how the band may be connected to plate 6 by its enlarged end 4, which passes freely through a slot at 17 when the screw is drawn back, but is caught between the edge of the slot and the washer 13 on 15 the end of screw 8 when this latter is tightened. The plate 6 may slide through a slot as in Figures 1 to 3, or under nibs 16 as in Figures 4 to 6.

Figures 9 and 10 illustrate a modification 20 wherein the plate 6 has its downwardly turned end engaged by a projecting pin at 18 on the end of screw 8, while the band is connected to plate 6 by being carried along the top thereof and looped through a slot 25 at 19. It will be seen from the plan view, Figure 10, that in this case the nibs 16 on the side plates 15 are wide enough apart to lie over the sides of plates 6 while the band passes over the middle portion clear of these 30 nibs. This construction is in many respects the most satisfactory in practice as the pull of the end of the band over the plates 6 is well balanced and does not tend to distort it appreciably as the screw 8 is tightened 35 up. The end 2 of the band, hooked into the slot in the base plate 3 is the detachable end in this case, the other end being fastened permanently to plate 6 when the band is applied.

40 Figure 11 shows a construction similar to that of Figure 8, but with the sliding plate inverted. It slides through a slot in lug 7 near the bottom thereof, and the end 4 of the band is gripped between a washer or 45 plate 13 on screw 8, and the edge of the slot at 17 in the end of plate 6. The head of the screw 8 may have a hole therein, and the rear end of the sliding plate 6 may also have a hole as in Figure 11, so that when the band 50 is tightened up, the screw can be locked by passing and sealing a wire 22 through these two holes.

Having thus described my invention what

I claim as new and desire to secure by Letters Patent is:—

55 1. A band clip device comprising a base plate having a lug and a nut carried thereby, a screw passing through said nut in a direction substantially parallel with the face of said base plate, a sliding plate member having a bent up face against which said screw bears, said sliding plate member being passed through and adapted to be guided by a slot in the lug on said base plate, a band, means for engaging one end of said band with the base plate, and means for engaging the other end of said band with said sliding plate member.

60 2. A band clip device comprising a base plate having a lug and a nut carried thereby, a screw passing through said nut in a direction substantially parallel with the face of said base plate, a sliding plate member having a bent up face against which said screw bears, said sliding plate member being 65 passed through and adapted to be guided by a slot in the lug on said base plate, a band, means for engaging one end of said band with the base plate, and a gripping member adapted to be tightened against the bent up face of said sliding plate member by the tightening of said screw, and adapted 70 to grip the other end of said band between said gripping member and the face of said sliding plate member.

75 3. A band clip device comprising a base plate of L-shape with its end projecting outwardly, a nut supported at the angle of the L of said base plate, a screw passing through said nut and through an aperture 80 in the projecting end of said base plate, a sliding plate with a bent end, means for guiding said sliding plate in the projecting end of said base plate, a band member adapted to be passed through an aperture in 85 said base plate and to have its one end doubled over while its other end is engaged with an aperture in said sliding plate, said screw being disposed in such manner as to exert pressure on the bent end of said sliding plate and to force it longitudinally over the doubled-over end of said band member while drawing out the other end of said band member which is engaged with said sliding plate.

100 CHARLES I. LOPDELL.
